UNITED STATES PATENT OFFICE.

OLIVER W. RANDOLPH, OF TOLEDO, OHIO.

HEATER FOR GRAIN-DRIERS.

1,262,841.

Specification of Letters Patent. Patented Apr. 16, 1918.

Application filed February 15, 1917. Serial No. 148,700.

To all whom it may concern:

Be it known that I, OLIVER W. RANDOLPH, a citizen of the United States, residing at Toledo, in the county of Lucas and State of 5 Ohio, have invented new and useful Improvements in Heaters for Grain-Driers, of which the following is a specification.

My invention relates to a heater for a grain drier, and has for its object to provide 10 an economical heater for the purpose that is adapted to utilize substantially all the heat produced by the combustion of fuel in a furnace of the heater, by first heating a large volume of air to a low temperature while 15 being drawn through the heating tubes of the heater by a forced draft of air drawn through the furnace of the heater and raised to a high temperature, and then mingling the forced draft of the furnace with the 20 greater volume of air drawn through the heating tubes, whereby the entire volume of air forced through the grain drier is raised to and automatically maintained at a desired mean temperature.

25 A further object is to commingle the gases of combustion with the heated air forced through the grain in the drier, whereby parasitic and other insect life infesting the grain is destroyed, and the grade and quality 30 of the grain is improved.

I accomplish these objects by the construction and combination of parts as hereinafter described and illustrated in the drawings, in which—

35 Figure 1 is a perspective view of a heater constructed in accordance with my invention.

Fig. 2 is a reduced top view of the same. Fig. 3 is a vertical section of Fig. 2 on 40 line $x-x$.

Fig. 4 is a vertical section of Fig. 2 on line $y-y$.

Fig. 5 is a perspective view of a pair of heater units nested together.

45 Fig. 6 is a side view of a number of heater units assembled together in their alternating order.

Fig. 7 is a section of Fig. 6 on line $z-z$. Fig. 8 is a perspective view of a baffle 50 plate.

Fig. 9 is a screen for the tops of the hoods. Fig. 10 is a perspective view of a hot air 55 damper, and

Fig. 11 is a diagrammatic view of the heater and its connections with a grain drier. In the drawings A designates a heater

constructed in accordance with my invention and comprising the furnace 1, the heater 2, the air mixing chamber 3, the heater hoods 4, and their connections 5 with 60 the mixing chamber, and a magazine fuel feed 6.

The furnace 1 comprises the rectangular metal casing 7 having a fire clay lining 8, a grate 9, the baffle plates 10 above the grate, 65 the draft door 11, and the fuel door 12.

The heater 2 which is mounted on the furnace wall over the front and rear portion of the grate 9, is built up of alternating unit sections a and b each comprising a rectangular frame 13 with integral transverse heating tubes 14, having their bores extending 70 through the sides of the frame.

The tops of the frames 13 are provided with rabbets 15 and their bottoms with the 75 tongues 16 complementary to the rabbets 15, and the corners of each frame are provided each with a web 17 perforated to receive a connecting rod 18 by which the units are securely bolted together, and to the furnace 80 casing.

The tubes 14 of the units b are arranged to extend horizontally above the spaces between the tubes of the section a and parallel therewith, whereby the tubes of one unit 85 operate as deflectors to direct the gases of combustion against the tubes of the other.

Two equal groups of alternating units a and b are formed and mounted respectively one on the front portion and the other on 90 the rear portion of the furnace casing and between the two groups is fitted the coal feed magazine 6 having a hopper shaped extension within the furnace chamber, adapted to deliver fuel centrally of the grate. 95

On the front and rear heater groups are mounted the hoods 4, the tops of which are connected by an arched duct 20 which supports a common flue stack 21.

At one side, the tubes of the two heater 100 groups open into the mixing chamber 3 to which the hoods 4 are also connected by the ducts 5. The mixing chamber 3 is also connected by a duct 23 having capacity equal to all the tubes of the heater with a 105 blower fan having connection with the air receiving hood H of a grain drier D and having the capacity to supply air sufficient for the grain capacity of the drier.

The ducts 5 connecting the hoods 4 with 110 the mixing chamber 3 are provided with the dampers 24 which are fixedly mounted

on the common arbor 25, one end of which is provided with a bell crank 26.

Centrally between the ducts 5, the mixing chamber 3 is also provided with a cold air duct 5' horizontally through which passes the arbor 25 upon which within the duct is fixedly mounted the damper 24' at right angles to the plane of the dampers 24, for a purpose hereinafter described.

10 The draft door 11 of the furnace is also provided with a bell crank 27, one arm of which is connected with the door, and the other by the chain 29 with one of the arms of the bell crank 26, which is operatively connected with a regulator automatically controlled by a thermostat introduced into the hood H of the grain drier D to which the heater is connected and operating as hereinafter described.

20 The stack 21 near its connection with the arched duct 20 is provided with a damper 21' adapted to be adjusted to entirely close the stack.

The mixer chamber 3 of the heater A is 25 connected as diagrammatically shown in Fig. 11 by the duct 23 with the blower B which is operatively connected by the driving belt C with a motor (not shown) and by the duct E with the hood H of the drier D. An

30 air compressor F is operatively connected by a belt f with the pulley e on the axle of the fan of the blower B and by a pipe h with the receiver R from which the pipe k extends to an air gage G connected to a 35 thermostat T installed in the hood H of the drier D, and adapted to control an air escape valve (not shown) of the gage G. The pipe k is also connected by a branch pipe k' with an air motor L connected to one arm of the bell crank 26 and adapted to 40 operate the bell crank in one direction against the resistance of a spring (not shown) that is adapted to normally and yieldingly hold the bell crank in a position 45 to open the dampers 24 and close the damper 24'.

Thus constructed the operation is as follows:—

The dampers 24 and 24' being in the relative normal position above described before 50 starting a fire in the furnace, the damper 21' in the stack 21 is fully opened and kept in that position until a bed of incandescent coal is on the grate of the furnace, after 55 which the fuel magazine is filled with hard coal or coke, the damper 21' is closed and the blower fan B is started, the suction of which draws air from the mixing chamber 3 thereby drawing air through the tubes 14

60 of the heater and also from the furnace chamber through the ducts 5 and the draft door 11 with the mixing chamber, whereby a forced draft through the grate is produced to maintain combustion of the fuel.

65 The tubes 14 are heated by the gases of com-

bustion passing around them on their way to the mixing chamber and in turn heat the air drawn through the tubes 14 into the mixing chamber.

The thermostat T being adapted by its 70 expansion at a pre-determined degree of heat to commence to close the air valve of the gage G and at a predetermined higher degree of heat to fully close the valve, the thermostat is made to automatically control the heat in the hood H of the drier D 75 as soon as the temperature of the air in the hood H reaches a degree partly closing the valve of the air gage, at which point the air pressure in the pipe K begins to rise 80 and to operate the motor L against the tension of its spring, and thereby partly closes the dampers 24 and opens the damper 24', and if the temperature in the hood H rises to the maximum the valve in the 85 gage G is fully closed and the motor L is thereby operated to fully close the dampers 24 and fully open the damper 24' whereby heated air and gases from the furnace are almost entirely cut off from the mixing 90 chamber and cold air is drawn through the duct 5' into the mixing chamber, whereby the temperature is immediately lowered in the hood H and the thermostat opens the valve of the gage G thereby reducing the 95 pressure in the pipe k and permits the spring of the motor L to again open the dampers 24 and close the damper 24', thus automatically regulating the degree of heat 100 in the drier hood H to a temperature between the maximum and minimum predetermined degrees.

By the construction shown and described I obtain an economical supply of air for a drier, heated to a substantially uniform 105 temperature, and by mingling the gases of combustion with the air supply for the drier, in addition to the drying of the grain, I thereby destroy all parasitic insectivora and the like infecting the grain, and thereby 110 improve the quality and grade of the grain.

The specific means shown and described for automatically regulating the dampers of my heater are commonly employed in heating and ventilating systems, and excepting in combinations with the blower and the dampers as means to regulate and control the commingling of the gases of combustion with the air drawn through the heater tubes and cold air duct, I do not 115 claim them as a part of my invention and do not limit myself thereto, as the same regulation may be accomplished by other thermostatically controlled regulators.

In constructing my dampers 24 and the 120 draft door they are preferably provided with perforations o, whereby when fully closed they will not entirely cut off all forced draft through the furnace.

The hoods 4 are preferably provided with 125

the screens 30, covering the openings to the ducts 5 extending from the tops of the hoods to the mixing chamber, whereby cinders and the like are prevented from entering the 5 mixing chamber with the gases of combustion.

It is manifest that a heater constructed and operating as shown and described, may be economically used for drying other material besides grain, and I therefore do not 10 limit myself to its use with grain driers alone.

What I claim to be new is—

1. A heater for supplying hot air for drying grain and other material, comprising a furnace, a heating chamber for the furnace, an air mixing chamber, air heating tubes extending through the heating chamber and adapted to supply air to the mixing chamber, 20 a duct connecting the heating chamber with the mixing chamber, an air duct adapted to connect the mixing chamber with the air intake of a blower fan, whereby air is drawn through the heating tubes and both 25 air and gases through the duct of the heating chamber into the mixing chamber, and means to vary the volume of air and gases drawn through the duct from the heating chamber to the mixing chamber, relative to 30 the volume drawn through the heating tubes, and to regulate the degree of heat of the air in the mixing chamber.

2. A heater for supplying hot air for drying grain and other material, comprising a furnace, a heating chamber for the furnace, an air mixing chamber, air heating tubes extending through the heating chamber and adapted to supply air to the mixing chamber, a duct connecting the heating chamber 35 with the mixing chamber, an air duct adapted to connect the mixing chamber with the air intake of a blower fan, whereby air is drawn through the heating tubes and both air and 40 gases through the duct of the heating chamber into the mixing chamber, and means to

vary the volume of air and gases drawn through the duct from the heating chamber to the mixing chamber, relative to the volume drawn through the heating tubes, and to automatically regulate the degree of heat 50 of the air in the mixing chamber.

3. In a heater for supplying hot air for drying grain and other material, the combination with the air receiving hood of a grain drier, a thermostat installed in the 55 hood, and a blower adapted to deliver air to the hood, of a heater comprising a furnace chamber having a grate, and a draft door adapted to admit air to the furnace chamber below the level of the grate, a heating chamber above the furnace chamber having heater tubes extending through the heater chamber, a mixing chamber adapted to receive air from the heating tubes, a duct connecting the blower with the mixing chamber 60 and adapting the blower to draw air through the tubes of the heater into the mixing chamber, an air duct connecting the heating chamber with the mixing chamber, and air duct connecting the mixing chamber 65 with the atmosphere, a damper controlling each inlet air duct connecting the mixing chamber with the heating chamber and with the atmosphere, the damper controlling the duct connecting the heating chamber with 70 the mixing chamber being normally open, and the damper controlling the air duct connecting the mixing chamber with the atmosphere being normally closed, and means connecting the thermostat of the drier hood 75 with the dampers and adapting the thermostat to automatically and reversely control the dampers.

In testimony whereof I have hereunto set my hand at Toledo, Ohio, this 12th day of February, 1917.

OLIVER W. RANDOLPH.

In presence of—

ALBERT T. GOORLEY,
RICHARD C. WATSON.
